UNITED STATES PATENT OFFICE.

WILLIAM H. COSTIGAN, OF SAUQUOIT, NEW YORK.

DESIGN FOR A CANDELABRUM.

46,046.

Specification for Design.

Patented July 7, 1914.

Application filed April 14, 1914. Serial No. 831,832. Term of patent 3½ years.

To all whom it may concern:

Be it known that I, WILLIAM H. COSTIGAN, residing at Sauquoit, in the county of Oneida and State of New York, have invented a new, original, and ornamental design for Candelabra, of which the following is a specification, reference being had to the accompanying drawing, forming part thereof.

The figure is a perspective view of a candelabrum showing my new design.

I claim:

The ornamental design for a candelabrum as shown.

WILLIAM H. COSTIGAN.
